UNITED STATES PATENT OFFICE

JOHN H. COSTENBAKER, OF NORFOLK, VIRGINIA

TOOTHBRUSH

Application filed December 19, 1930. Serial No. 503,581.

This invention relates to toothbrushes and has for an object the provision of means whereby the brush head or bristles may be positioned relative to the handle, so that all 5 of the inner and outer surfaces of the teeth may be properly brushed by a movement parallel with the length of the teeth for the removal of matter lodged between the teeth.

Another object of the invention is the provision of a brush of the above character which will render the proper way of brushing the teeth easier than the improper way, so that the brush will act to educate the user 10 in the proper method of cleaning or brushing his teeth.

Another object of the invention is the provision of a brush which, in addition to the above and other advantageous features, is 15 simple in construction, and may be easily and quickly adjusted to the desired position for use either with the right or left hand.

With the above and other objects in view, the invention further includes the following 20 novel features and details of construction, to be hereinafter more fully described, illustrated in the accompanying drawings and pointed out in the appended claims.

In the drawings:—

Figure 1 is a side elevation of the invention.

Figure 2 is an end view.

Figure 3 is an elevation with parts in section.

Figure 4 is a top plan view.

Figures 5, 6 and 7 are sectional views taken respectively on the lines 5—5, 6—6 and 7—7 of Figure 3.

Referring to the drawings in detail where-in like characters of reference denote corresponding parts, the reference character 10 indicates the handle of the brush which may be of any suitable character whereby a firm and comfortable grip may be obtained. One end of the handle is provided with a sleeve 40 11 which may be formed thereon or attached to the handle by any desired means. This sleeve accommodates a plug 12 which is provided with a reduced portion 13, the latter extending into the bore of the sleeve as shown in Figure 3 of the drawings. Inward move-

ment of the plug is limited by a collar 14 which extends around the bore of the sleeve, and a shoulder 15 which is provided on the plug 12. The plug may thus be rotated or moved axially within the sleeve.

The plug is provided with a bore 16 through which extends the shank 17 of a brush head 18, the latter carrying bristles 19. One end of the shank 17 is threaded to receive a nut 20 which bears against the adjacent end of the plug and removably holds the shank in place.

Positioned within the space provided between the inner wall of the sleeve 11 and the periphery of the reduced portion 13 of the plug, is a coiled spring 21. One end of this spring bears against the collar 14 and its opposite end bears against an annular member or nut 22 which threadedly engages the adjacent end of the plug 13. The plug is thus yieldingly held against outward longitudinal movement. The edge of the sleeve 11 is provided with spaced notches 23 which are adapted to receive spaced teeth 24 which extend from the opposed shoulder 25 of the plug 12. Any suitable number of these notches and teeth may be provided. It is believed however that four notches and four teeth are preferable so that four different 70 adjustments of the brush with respect to the handle 10 may be obtained.

As will be seen by reference to Figures 1 and 3 of the drawings, the shank 17 is disposed at an obtuse angle with respect to the handle 10 and may be rotatably adjusted to any of the positions provided by the notches 23 and teeth 24. In order to rotatably adjust the brush, the nut end of the plug 12 is forced slightly inward so that the teeth will clear the notches, whereupon the brush may be rotated until the teeth again enter the notches. Four different adjusted positions of the brush are illustrated in Figure 2 of the drawings, the full line position of this figure showing the brush adjusted for brushing the upper 80 surface of the lower teeth. By reversing the position of the brush as indicated by the dotted lines at A in Figure 2, the lower surface of the upper teeth may be conveniently brushed, while the dotted lines B indicate 85

the position of the brush for brushing the inner surfaces of the teeth upon the left side of the mouth and the outer surfaces of the teeth upon the right side of the mouth, while the 5 dotted line position C indicates the position of the brush for brushing the inside of the teeth upon the right side of the mouth and the outside of the teeth upon the left side of the mouth, while either of the positions B 10 and C may be utilized for brushing the outside of the front teeth or the inside of the front teeth, depending upon which hand holds the brush.

By reason of the arrangement of the brush 15 bristles with respect to the handle and the positions into which these bristles may be adjusted, the most convenient direction of movement of the bristles over the teeth will be vertical or in the direction of the length 20 of the teeth. The invention will thus influence the user to brush the teeth in a proper manner for the removal of particles of food lodged between the teeth, instead of brushing 25 them transversely of the teeth as with the straight handled brush. This transverse brushing of the teeth forces food to collect between the teeth and fails to remove the film along the side edges of the teeth. A brush 30 constructed in accordance with the present invention renders transverse brushing of the teeth difficult.

By reference to Figure 3 of the drawings it will be seen that the shank 17 is removably 35 secured within the plug 12, so that when the brush bristles become worn, a new brush may be secured within the plug. It will not be necessary therefore to renew the entire brush and handle. Independent rotary movement 40 of the shank within the plug is prevented by the cross sectional shape of the shank and plug at one end thereof, as shown in Figure 6.

The invention is susceptible of various 45 changes in its form, proportions and minor details of construction and the right is herein reserved to make such changes as properly fall within the scope of the appended claims.

Having described the invention what is claimed is:—

- 50 1. In a toothbrush, a handle, an angularly disposed socket at one end thereof, a brush carrying shank, a plug carried at the inner end of the shank and rotatably and axially movable within the socket, and spaced means surrounding the socket and engaging the plug to hold the shank against rotation.
- 55 2. In a toothbrush, a handle, an angularly disposed socket at one end thereof, a brush carrying shank, a plug having a reduced portion carried at the inner end of the shank and rotatably and axially movable within the socket, and yieldable means within the socket and surrounding the reduced portion of the plug to resist axial movement of the shank.
- 60 3. In a toothbrush, a handle, an angularly

disposed socket at one end thereof, a collar formed internally of the socket adjacent one end thereof, a brush carrying shank, a plug having a reduced portion carried at the inner end of the shank and rotatably and axially movable within the socket, yieldable means to resist axial movement of the shank, said means surrounding the reduced portion of the plug and being disposed within the socket and contacting at one end with said collar.

In testimony whereof I affix my signature.

JOHN H. COSTENBADER.
